UNITED STATES PATENT OFFICE.

OTTO BANNER, OF EASTON, PENNSYLVANIA, ASSIGNOR TO INGERSOLL-RAND COMPANY, OF JERSEY CITY, NEW JERSEY, A CORPORATION OF NEW JERSEY.

STEAM-TURBINE.

1,177,917.

Specification of Letters Patent.

Patented Apr. 4, 1916.

Application filed August 27, 1914. Serial No. 858,813.

To all whom it may concern:

Be it known that I, OTTO BANNER, a subject of the Emperor of Germany, residing at Easton, in the county of Northampton and State of Pennsylvania, have invented 5 a certain new and useful Improvement in Steam-Turbines, of which the following is a specification.

This invention relates to fluid operated turbines, and more particularly to turbines 10 adapted to be used through a considerable range of loads. In my co-pending application, Serial No. 834,890 filed April 28th, 1914, I have described a turbine for this purpose 15 which comprises a high pressure stage, a series of low pressure stages, which continually receive the exhaust from the high pressure stage and a second normally inactive low pressure stage consisting of a velocity com- 20 pounded wheel situated in the exhaust chamber of the turbine. In this turbine a series of valve controlled nozzles are used, those on the high pressure wheel being supplied with the live steam and those on the nor- 25 mally inactive wheel being supplied from the exhaust of the high pressure wheel. Under conditions of normal load only the nozzles on the high pressure wheel are opened while under greater load conditions further 30 nozzles on the high pressure wheel are opened and at the same time nozzles leading from the exhaust of the high pressure wheel to the normally inactive wheel, the pressure of the fluid passing through 35 the normally supplied low pressure stages being thus maintained low enough for the normal low pressure stages to operate efficiently. In this turbine the high pressure nozzles are designed to expand the steam 40 from its original pressure to a pressure con- siderably above the exhaust pressure of the turbine, while the nozzles of the normally inactive low pressure stage are designed to expand the steam from the pressure at the 45 exhaust of the high pressure wheel to ap- proximately the exhaust pressure of the tur- bine, or a little above, the wheels being of such a diameter that they will efficiently abstract velocity of the steam flowing from 50 their respective nozzles.

The object of the present invention is to simplify the construction of the regulating mechanism without any material decrease in the over all efficiency of the turbine, and 55 to do this the high pressure steam is sup-

plied under high load conditions directly to the normally inactive wheel, this being provided with nozzles of such a design that they expand the steam all the way from inlet pressure to, or somewhat above, the ex- 60 haust pressure, while this normally inactive wheel is made of sufficient diameter and with two or more rows of blades so that velocity of the steam can be efficiently abstracted. 65

A practical embodiment of the invention is shown in the accompanying drawings, in which,

Figure 1 shows a side elevation of a tur- 70 bine with the upper half in section, and Fig. 2 shows a plan view of the turbine partly broken away to show the details.

In the drawings, the turbine is shown as comprising a casing 1 which is divided by diaphragms or partitions 2, 3, 4 and 5 into 75 a high pressure chamber 6, low pressure chambers 7, 8 and 9, and an exhaust chamber 10, which preferably leads by an ex- haust conduit 11 to a condenser, (not shown). 80

In the high pressure chamber 6 rotates a high pressure wheel 12, which is here shown as having a single row of blades. In the low pressure chambers 7, 8 and 9 low pres- 85 sure wheels 13, 14 and 15 rotate, respectively, while in the exhaust chamber a further low pressure wheel 16 rotates. These low pres- 90 sure wheels may or may not be, as shown, of smaller diameter than the high pressure wheel 12. In the exhaust chamber 10 also rotates a wheel 17 for use under high load conditions. This, as shown, has two rows of blades, 18 and 19, although more or less rows may be used if desirable. Steam or 95 other operating fluid is introduced to the turbine through a conduit 20 which connects with a series of steam chambers 21, 22, 23 and 24. From the steam chambers 21 and 22 steam is led to and directed against the blades of the high pressure wheel 12 by a 100 series of nozzles 25 and 26. These nozzles 25 and 26 are so designed that they allow a large pressure drop, the steam expanding therein from the line pressure to a compa- 105 ratively low pressure, but one which is con- siderably above the exhaust pressure of the turbine. The steam from these nozzles af- 110 ter passing through the high pressure wheel 12 passes consecutively through the low pressure wheels 13, 14, 15 and 16 through

nozzles 27, 28, 29 and 30, respectively, in the diaphragms 2, 3, 4 and 5, the remaining pressure drop of the steam being thus utilized. From the steam chests 23 and 24 steam can 5 pass through conduits 31 and 32 to nozzles 33 and 34 which lead the steam to and direct it against the blades of wheel 17. These nozzles 33 and 34 are so designed that they permit the expansion of the steam from line 10 pressure to or somewhat above the exhaust pressure of the turbine and the blades of the wheel 17 are designed to efficiently abstract the high velocity produced by the large expansion, it being evident that the wheel 15 17 must be of considerable diameter to accomplish this result. The steam under line pressure is admitted from the conduit 20 to the steam chambers 21, 22, 23, 24, by valves 35 which are controlled by a regulating 20 mechanism 36 of any desired construction, such as shown, for example, in my copending application Serial No. 830,843 filed April 10, 1914. This regulating mechanism 36 is so arranged that steam is first admitted 25 to chamber 21, passing through nozzles 25 and then under increasing load conditions to chambers 22, 23 and 24, the steam from the chambers 23 and 24 passing directly to the wheel 17. By this construction, the pressure 30 in the chamber 6 is not allowed to rise above a point where the steam will not be able to pass efficiently through the low pressure wheels 13, 14, 15 and 16, the steam required for higher loads passing directly to 35 the wheel 17. The regulating mechanism, therefore, is considerably simplified without any appreciable loss in efficiency.

It is to be understood that while the present showing and description discloses only 40 one specified modification of the invention, other forms and modifications are included in the spirit and scope thereof, as expressed in the claims.

What I claim is:

45 1. In a steam turbine, a high pressure

wheel, and a series of low pressure wheels receiving steam therefrom, a normally inactive wheel for high loads located in the exhaust of said low pressure wheels, and means for admitting live steam to said high 50 load wheel only under high load conditions.

2. In a steam turbine, a high pressure wheel and a series of low pressure wheels receiving steam therefrom, a single velocity compounded wheel of larger diameter for 55 use under high loads located in the exhaust of said low pressure wheels, nozzles for admitting steam to said high pressure wheel, nozzles for admitting steam to said high load wheel, and regulating mechanism for 60 admitting steam serially to said high pressure nozzles and to said high load wheel nozzles under increasing load conditions.

3. In a steam turbine, a high pressure stage and a series of low pressure stages receiving steam therefrom, a wheel for high loads located in the exhaust of the turbine, nozzles for admitting steam to said high pressure wheel, and nozzles for admitting steam to said high load wheel, said last 70 named nozzles being designed to expand the steam from line pressure to a pressure lower than said first named nozzles.

4. In a steam turbine, a high pressure stage and a series of low pressure stages receiving steam therefrom, a wheel for high loads located in the exhaust of the turbine, nozzles for admitting steam to said high pressure wheel, and nozzles for admitting steam to said high load wheel, said last 80 named nozzles being designed to expand the steam from line pressure to a pressure above exhaust pressure.

In testimony whereof I have hereunto set my hand.

OTTO BANNER.
